UNITED STATES PATENT OFFICE.

HENRY D. METCALF, OF CASEY, ILLINOIS.

FAUCET-OPERATING MECHANISM.

1,093,452.

Specification of Letters Patent. Patented Apr. 14, 1914.

Application filed August 27, 1912. Serial No. 717,354.

To all whom it may concern:

Be it known that I, HENRY D. METCALF, a citizen of the United States, residing at Casey, in the county of Clark and State of Illinois, have invented new and useful Improvements in Faucet-Operating Mechanisms, of which the following is a specification.

This invention relates to faucets; and it 10 has for its object the provision of a faucet wherein will be included means for yieldingly holding the plug thereof in a closed position relatively of the discharge and intake ends respectively of the plug casing.

15 Another object of the invention is to provide means whereby the valve is normally held closed and the operating means sustained in an operative position.

Figure 1 is a side view of the faucet and 20 the operating mechanism therefor. Fig. 2 is a section through the faucet.

The faucet 1 includes a casing 2 which is mounted in any suitable well known manner in the feed pipe 3 of a liquid supply, 25 not shown. The pipe 3 herein represented is designed particularly for use upon beer dispensing apparatus, apparatus for dispensing syrups at soda fountains or the like, being vertically disposed and being terminally extended at its upper end into a discharge spout 4. This spout may be disposed above the plane of a counter whereby a vessel may be placed therebeneath when it is desired to fill the same. The casing 2 30 is provided with a rotary plug 5 in which is formed a portway 6. The stem 7 of the plug is journaled in the opposite walls of the casing and at one end the stem has secured thereto a lever 8 which may be operated to effect different adjustments of the plug whereby the portway 6 can be brought in direct communication with the pipe 3 to permit the discharge of the liquid when desired.

45 The casing 2 has a bracket 9 secured thereto, and as illustrated said bracket is provided with a portion 10 which is disposed in concentric relation with the axis of the plug 5. The portion 10 forms a guide for the lever 8, the latter having an arcuate passage 11 therein through which said portion 10 extends, and as illustrated the lever is provided with a socket portion 12 which is spaced from a shoulder 13 on the bracket 50 9 whereby to form a companion rest or abutment for the respective terminals of an

extensile spring 14. The upper terminal of the portion 10 is bent laterally to form a stop 15 at a point above the plane of the lever 8 whereby to lie directly in the path of the lever and to engage the same to limit the movement thereof in one direction, the said stop being disposed in spaced relation to the adjacent end of the valve casing and adapted to be bent into the longitudinal 60 plane of the passage and socket respectively to permit the removal of the lever when it is desired to remove the valve from the casing.

The actuating mechanism of the faucet 70 comprises a foot treadle 16 which is pivoted at 17 upon a suitable support A. Companion bell-crank levers 18 and 19 are also pivoted upon the support A, and as shown 75 said levers have their depending arms 19 operatively connected together through the medium of a rod 20 whereby adjustment of one lever will result in a proper adjustment of the other lever to influence the plug 5. The arm 21 of the lever 18 is connected by 80 a link 22 with the inner end of the foot treadle 16, while the arm 23 of the companion lever 19 has detachable connection with a draft rod 24, the latter having its upper end operatively associated with the 85 lever 8 as shown.

Now that the details of construction of the mechanism are clearly described it is stated that the spring 14 serves singly as a 90 means for normally holding the plug 5 in a closed position and for sustaining the effective controlling end of the treadle 16 in proper position, whereby when pressure is applied to the treadle an adjustment of the plug 5 will be made so that the portway 6 95 will be brought into direct communication with the feed pipe 3. The mechanism is such that the operator may use both of his hands in caring for or in manipulating the 100 glasses or vessels during the filling operation. Immediately on releasing pressure from the treadle 16 the companion elements of the mechanism will respond under proper action of the spring 14 and as a consequence 105 further discharge of the liquid will be checked. Should the companion bell-crank levers 18 and 19, the connection 20, the link 22 and the treadle 16 become casually deranged to such extent that they would refuse to operate, the lower end of the rod 24 110 can be quickly disconnected from the arm 23 of the lever 19 so that the lever 8 of the

faucet plug can be controlled positively by the hand of the operator.

I claim:—

- 5 A valve comprising a casing having a rotary plug therein, a lever fixed to the stem of the plug and provided adjacent its free end with a socket and a passage respectively, the latter opening into the former, an articulate guide member having one end fixedly set 10 cured to the lower end of the casing and having its free end extended through the socket in the lever, the said free end of the guide being terminally bent to provide a laterally extending arm disposed in spaced 16 relation toward the top of the valve casing and adapted to act as a stop to limit the up-

ward movement of the lever, the said stop being adapted to be bent in the longitudinal plane of the passage in the lever to permit the removal of the lever from the guide, a 20 shoulder formed on the guide member adjacent the lower end thereof, and a spring interposed between the shoulder and the socket and bearing against the lever so as to hold the latter normally against the said 25 laterally extending arm.

In testimony whereof I affix my signature in presence of two witnesses.

HENRY D. METCALF.
